UNITED STATES PATENT OFFICE.

CHARLES A. McGRAW, OF McGRAW, NEW YORK, ASSIGNOR TO THE McGRAW MANUFACTURING COMPANY, OF McGRAW, NEW YORK.

SERVING DEVICE.

1,116,605.

Specification of Letters Patent.

Patented Nov. 10, 1914.

Application filed May 28, 1913. Serial No. 770,511.

To all whom it may concern:

Be it known that I, CHARLES A. McGRAW, a citizen of the United States of America, residing at McGraw, in the county of Cortland and State of New York, have invented 5 certain new and useful Improvements in Serving Devices, of which the following is a specification.

This invention relates to rotary servers 10 for dining tables, and one of the principal objects of the invention is to provide an ornamental rotary device for facilitating the service of such articles as salt, pepper, mustard, salads, bread, sugar, cream, coffee, 15 water, cakes, etc., and to provide means whereby any person may readily bring to his hand the article which he desires.

Another object of the invention is to provide a rotary server which will not occupy 20 much space upon the center of a table and in which the supporting element is disposed a sufficient height from the table to permit articles to be placed underneath it.

Still another object of the invention is to 25 provide a serving device which is especially adapted for dinner or luncheon service, for card parties, afternoon teas, at the club, on the lawn and on the veranda for a lunch and for holding punch bowls and glasses, etc., 30 and which is ornamental as well as useful.

These and other objects may be attained by means of the construction illustrated in the accompanying drawings, in which:

Figure 1 is a side elevation of a serving 35 device made in accordance with this invention; Fig. 2 is a top plan view of the same; Fig. 3 is a central vertical section through the same; Fig. 4 is a central vertical section taken through a slightly modified form 40 of my invention; Fig. 5 is a detailed view of the post and integral supporting element to which the rotary top is to be secured, as shown in Fig. 3.

Referring to the drawings for a more particular description of the invention, the 45 numeral 1 designates the base member which is preferably of metal and of sufficient weight to give stability to the entire device and to prevent it from tipping or 50 displacement. The base 1 is hollowed out at its under side as at 2 and the outer rim which is adapted to rest upon the table is provided with a frictional cushion of felt or similar fabric 3 which prevents the lateral 55 movement of the entire device and serves

to aid in holding the device firmly in place against tipping or other movement. The base 1 is provided with an upwardly projecting shank 4 having an internal bore or socket 5. The upper end of the shank 4 may 30 be substantially plain as shown at 6, and the socket 5 extends a considerable distance from the upper shoulder 6 to a point near the bottom of the base 1.

A rotary post is fitted in the socket 5 and 65 comprises the reduced member 7 extending nearly the entire length of the socket 5 and provided at its upper end with an integral supporting member 10, said supporting member being plain upon its upper face, 70 and connected to this member by means of suitable cement 11 is a top 12 of circular form. The top 12 is preferably formed of plate glass and at its outer edge is ground as at 13, so that by applying the thumb or 75 forefinger, the user may readily rotate the top 12 to bring to his hand any article supported on top of the server without soiling the top of the plate glass with a finger mark. 80

As shown in Fig. 4, the base member 1^a is provided with a hollow under portion 2^a and with a surrounding supporting rim 3^a having a felt or other frictional pad 4^a secured thereto. The member 1^a is bored vertically from the top of the shank 5^a to the bottom and the shank 5^a is also provided with a squared upper shoulder 6^a. The post 7^a extends entirely through the base member 1^a and is screw threaded at the lower 90 end, to fit the threaded lower end of the bore of the shank. Lock nuts 9^a are fitted to the lower end for holding the post firmly in position. The socket member 10^a, as shown in Fig. 4, is provided with a socket 11^a in which 95 the post 7^a is fitted. The supporting element 12^a is connected to the plate glass top 12 by means of cement or other suitable adhesive material 11 in a manner similar to that already described in reference to Figs. 1, 2 100 and 3, and said top, the member 12^a and the socket member 10^a freely revolve on the post 7^a.

From the foregoing, it will be obvious 105 that a serving device made in accordance with my invention is comparatively simple in construction, can be rotated freely without soiling the top of the same, to the desired position to serve any article resting upon the top; that the device is ornamental 110

in appearance, does not obstruct the view across the table and is sufficiently high to permit articles to rest on the table underneath the outer edge of the top.

5 I claim:

A serving device for dining tables comprising a base having a hollowed out under portion and a frictional pad surrounding the bottom of the same to prevent movement 10 of the device, said base having a socket formed therein, a post fitted to rotate in

said socket, said post having an integral enlarged supporting element at its upper end and a plane flat plate glass disk connecting to said element to rotate therewith.

In testimony whereof I affix my signature in presence of two witnesses.

CHARLES A. McGRAW.

Witnesses:

CLARENCE FRALICK,
MARGUERITE SHORT.
